DESIGN FOR A STICK FOR SPINNING BALL

John Palmieri, New York, N. Y.

Application February 5, 1944, Serial No. 112,462

Term of patent 3½ years

(Cl. D34—5)

To all whom it may concern:

Be it known that I, John Palmieri, a citizen of the United States, residing at New York, in the county of New York and State of New York, have invented a new, original, and ornamental Design for a Stick for Spinning Ball, of which the following is a specification, reference being had to the accompanying drawing, forming a part thereof.

In the drawing:

Fig. 1 is a side elevational view of a stick for spinning ball, showing my new design.

Fig. 2 is an edge view of the same.

I claim:

The ornamental design for a stick for spinning ball, as shown.

JOHN PALMIERI.
